UNITED STATES PATENT OFFICE.

SAMUEL SCHNELLING, OF CHICAGO, ILLINOIS.

DESIGN FOR A FINGER RING.

Application filed July 15, 1922. Serial No. 3,093. Term of patent 3½ years.

To all whom it may concern:

Be it known that I, SAMUEL SCHNELLING, a citizen of the United States, residing at Chicago, in the county of Cook and State of Illinois, have invented a new, original, and ornamental Design for Finger Rings, of which the following is a specification, reference being had to the accompanying drawing, forming part thereof.

Fig. 1 is an edge elevation of my new design of ring.

Fig. 2 is a top plan view of my new design of ring.

I claim:

The ornamental design for a finger ring as shown,

SAMUEL SCHNELLING.
